UNITED STATES PATENT OFFICE

WILLIAM J. HOSKYN, OF DETROIT, MICHIGAN, ASSIGNOR TO BRIGGS MANUFACTURING COMPANY, OF DETROIT, MICHIGAN, A CORPORATION OF MICHIGAN

TRIMMING-MATERIAL ASSEMBLY

Application filed August 2, 1926. Serial No. 126,551.

This invention relates generally to vehicle bodies and consists of certain novel features of construction, combinations and arrangements of parts as will be more fully described and particularly pointed out in the appended 5 claims.

In the present state of the art it is usual to conceal the top and side frame members of vehicle bodies by means of suitable cloth linings. Heretofore the problem of attaching such linings has been comparatively easy for the reason that the bows and frame work of the body were formed of wood. In such instances tacks or other similar securing means 10 could be used. However vehicle bodies are now being made wherein the top bows and side frame members are formed of metal, hence new problems of attaching the linings to such parts have been presented. With the 15 present invention these problems have been solved in a very simple and efficient manner as will be set forth in detail hereinafter described.

In the accompanying drawings:

20 Figure 1 is a fragmentary perspective view of a vehicle body embodying my invention.

Figure 2 is a vertical sectional view taken on the line 2—2 of Figure 1.

Figure 3 is a fragmentary perspective view 30 of the vehicle body with the panels of trimming material removed.

Figure 4 is a detail perspective view of the panels of trimming material with the fasteners applied thereto.

35 Referring now to the drawings, wherein there is disclosed a vehicle body similar to that disclosed in my co-pending application No. 125,040 filed July 26, 1926, 1 and 2 respectively are upper and lower side panels, 40 3 and 4 respectively are upper and lower back panels and 5 is the top of a vehicle body of the closed type. As shown, the side panels 1 and 2 are arranged in the same vertical plane and are secured together at their adjacent edges; likewise the upper and lower back panels 3 and 4 are arranged in a common vertical plane and are secured together at their adjacent edges. To provide a rigid joint the upper panels 1 and 3 are secured 45 together at their adjacent edges and the 50

lower panels 2 and 4 are secured together at their adjacent edges. To stiffen and reinforce the construction, I have provided suitable metal strips 6, 7, 8 and 9 respectively. As shown, the strip 6 has an outwardly projecting lateral flange 10 and has an inwardly 55 projecting depending L-shaped rabbet portion 11. Suitable bolts 12 and nuts 13 are preferably used to secure the strip 6 to the side panels 1 and 2. The strip 7 is similar 60 in construction to the strip 6 and is secured by bolts 14 and nuts 15 to the back panels 3 and 4 respectively. The strips 8 and 9 are preferably welded to the panels 1 and 3 respectively at the upper edges thereof so as 65 to support the top 5, which may be of the type disclosed in my co-pending application No. 125,039 filed July 26, 1926, and are provided at their inner edges with narrow upstanding flanges 16 and 17 respectively. 70

To provide a neat interior finish I have provided panels 18 and 19 respectively of trimming material that are detachably secured by clips 20 and 21 respectively to the strips 6, 7, 8 and 9. As shown, these panels 75 18 and 19 have a common covering of fabric and are provided with the card board backing panels 22 and 23 respectively. Any suitable means such as a strip of fabric glued to the adjacent ends of the panels 22 and 23 80 will suffice as a hinge to permit the panels 18 and 19 to conform readily to the corner formed by the panels 1, 2, 3 and 4 respectively. To facilitate the assembly, the clips 20 have prongs 25 rigidly secured to the 85 panels 22 and 23 at the upper edges thereof, and are provided at their upper ends with the hooked portions 26 that are engageable with the upstanding flanges 16 and 17 respectively of the strips 8 and 9, while the clips 21 have prongs 28 rigidly secured to the panels 22 and 23 at the lower edges thereof and are bent around the lower edges of the depending flanges 29 and 30 respectively 90 of the strips 6 and 7. 95

Thus, from the foregoing description it will be apparent that the panels 18 and 19 of trimming material may be easily and quickly secured to the frame work of the vehicle body to provide a neat interior finish. If desired 100

the trimming material may be readily removed by merely bending the end portions of the clips 21 out of engagement with the depending flanges 29 and 30 and then disengaging the hooked portion 26 from the upstanding flanges 16 and 17. The clips 20 and 21 are simple in construction and are cheap to manufacture. Moreover they may be quickly secured to the backing panels 22 and 23 and applied to the anchorage strips 6, 7, 8, and 9 respectively. This obviates the necessity of providing separate securing elements such as are now commonly used for attaching trimming material to the frame work of vehicle bodies, hence a considerable saving in time, labor and material has been effected.

While it is believed that from the foregoing description, the nature and advantage of my invention will be readily apparent, I desire to have it understood that I do not limit myself to what is herein shown and described and that such changes may be resorted to when desired as fall within the scope of what is claimed.

What I claim as my invention is:

1. A side wall structure for vehicle bodies comprising a metal panel, a panel of fabric trimming material upon the inner side of said metal panel, vertically spaced substantially horizontally disposed strips rigidly secured to said metal panel and projecting laterally inwardly therefrom, and means for supporting said panel of trimming material from said metal panel including fasteners rigidly secured to said panel of trimming material and detachably engaging the inner lateral edge portions of said strips.

2. A wall structure for vehicle bodies comprising upper and lower panels having portions secured together, a top supporting member secured to said upper panel at the upper edge thereof and having an upturned flange at its inner edge, a panel of fabric trimming material upon the inner side of said panels, and securing means for said panel of trimming material including fasteners secured to said trimming material and having hooked portions engaging the upstanding flange aforesaid.

3. A wall structure for vehicle bodies comprising upper and lower panels having portions secured together, a strip secured to the upper panel at the upper edge thereof and having an upturned flange at its inner edge, a reinforcing strip secured to one of the panels aforesaid and having a depending flange, a panel of fabric trimming material upon the inner side of said panels and securing means for said panel of trimming material including fasteners secured to said trimming material and having hooked portions engaging the upstanding flange aforesaid, and other fasteners secured to said trimming material

and having portions bent around the lower edge of said depending flange.

4. A wall structure for vehicle bodies comprising a metal panel, a panel of fabric trimming material upon the inner side thereof, an anchorage strip for said trimming material secured to said metal panel and having a depending flange, a second anchorage strip secured to said metal panel above the strip aforesaid and securing means for said panel of trimming material including fasteners projecting from said panel of trimming material and connected to said second anchorage strip, and other fasteners having portions projecting from said panel of trimming material and bent around the lower edge of said depending flange.

In testimony whereof I affix my signature.

WILLIAM J. HOSKYNS.
